UNITED STATES PATENT OFFICE.

ALBERT R. THOMPSON, OF SAN JOSE, CALIFORNIA, ASSIGNOR TO ANDERSON-BARN-GROVER MFG. CO., OF SAN JOSE, CALIFORNIA, A CORPORATION OF CALIFORNIA.

MACHINE FOR TREATING CANNED GOODS.

Application filed August 18, 1922. Serial No. 582,622.

REISSUED

To all whom it may concern:

Be it known that I, ALBERT R. THOMPSON, a citizen of the United States, residing at San Jose, in the county of Santa Clara and 5 State of California, have invented certain new and useful Improvements in Machines for Treating Canned Goods, of which the following is a specification.

My invention relates to that class of machines and apparatus used in the canning art, in which the canned goods while undergoing treatment are carried through a receptacle in a definite path along a track composed of a fixed helically directed rail lying 10 near the inner circumference of the shell, and a reel within the fixed rail and rotating about the axis thereof, said reel carrying a peripheral series of rails parallel with its axis and coacting with the fixed rail to support the cans and effect their travel in a helical path from their point of entrance into the receptacle to their point of discharge therefrom. Examples of these machines are those known as "cookers" in which the 15 canned goods are heat-treated; and those called "coolers" in which the previously cooked canned goods are subjected to a lower temperature to cool them.

In machines of this type, the common 20 practice has been to carry the fixed helically directed rail-member of the can-track, upon a series of longitudinal stringers supported in the receptacle and spaced from its walls. I have found, however, that a simpler construction is to bolt or rivet said rail member 25 directly to and against the wall of the receptacle in which case said receptacle must of course be of circular cross section. But this 30 presents a difficulty of draining the receptacle of the treating liquid, namely the water used therein, since a portion of the water will remain in the bottom between the coils of the helical rail if bolted directly against the receptacle wall, and will not drain out.

Also, especially in the case of cookers, which 35 require the inclusion within the receptacle of a steam-pipe for heating the water, the disposition of the helical rail directly against the receptacle wall, leaves no room for the 40 steam pipe, which must, necessarily, be outside of the sphere of rotation of the reel member of the can-track.

I have heretofore, as disclosed by my Patent No. 1402193, dated January 3, 1922,

sought to remedy these difficulties by so distorting the wall of the receptacle from its circularity as to form an underlying trough-like drain chamber opening directly in the interior of the receptacle, and having the coils of the helical rail bridge the opening. I have, however, found, in practice, that such construction, notwithstanding the riveting effect of the helical rail tending to keep the severed and distorted walls from spreading, is faulty, especially in receptacles such as pressure cookers or coolers, and that under high internal pressure the opening at the bottom is a dangerous constructive factor in that any yielding of the receptacle walls tending to distort the can path is fatal to the operation of the machine, as an uninterrupted precise can-stream flow through the receptacle is absolutely essential to success.

The object of my invention then, is to provide simple and effective means by which the receptacle in which the fixed rail is disposed directly against its wall, may be rigidly circumferentially continuous and still may be fully drained, and may also have a space or chamber for the inclusion of a steam pipe.

With these ends in view, my invention consists in the novel machine or apparatus for treating canned goods, which I shall now fully describe by reference to the accompanying drawings, in which—

Fig. 1 is a longitudinal, broken section, of my improved machine or apparatus.

Fig. 2 is an end view of the same, partly in section.

1 is the receptacle of the machine, circular in cross section and provided with an inlet indicated at 2 in Fig. 1, and an exit, indicated at 3, for the canned goods which pass through it.

Within the receptacle and bolted or riveted directly to and against its wall is the fixed rail 4. This rail, which is preferably of T-section with its leg portion extending inwardly is helically directed throughout substantially the length of the receptacle, and forms one member of the can-track. The other member of said track comprises an annular series of spaced rails 5, preferably of angle section, lying and revolving within the fixed helical rail 4, in such relation thereto that the cans are carried and sup-

ported between the rail 4 and rails 5, the latter being parallel to their axis of rotation, whereby the can path is a helical one throughout the length of the receptacle, all 5 as is now well known and common in practice. The rails 5 form the periphery of a reel having end heads 6 and a driving shaft 7.

Below the receptacle 1 is a longitudinally 10 extending header pipe 8, into one end of which is fitted an inlet water pipe 9, and in its other end is a drain 10. Leading upwardly from the header pipe 8 are the drain 15 pipes 11, entering the receptacle bottom, each at a point between the coils of the fixed helix rail 4.

It will now be seen that, notwithstanding the disposition of the rail 4 directly against the receptacle wall, all the treating water 20 within the receptacle may be drained out as occasion requires.

In the case of a cooker, where a source of heat must be provided, the header pipe 8 and drain pipes 11 being outside of the fixed 25 rail 4, serves as a means for introducing and housing a stem pipe 12.

In this improved construction, it will be seen that the circular receptacle is unbroken and may be made as capable of resisting internal pressure as the circumstances require, and still it may be fully drained and convenient provision made for introducing steam.

I claim:

35 1. A machine for treating canned goods comprising a receptacle circular in cross section and having a can inlet and a can exit; a fixed helically directed rail secured to the

receptacle wall and lying against the inner surface thereof, said rail forming one member 40 of a can track through which the cans are advanced through the receptacle; a rotatable annular series of spaced rails within the fixed helically directed rail, parallel with its axis and forming the other member of said can track; a header pipe outside of and longitudinally underlying the receptacle; a plurality of drain pipes leading from the header pipe and opening into the receptacle 50 between the coils of the helically directed rail therein, and means for introducing to the receptacle a temperature controlling medium through said header pipe and drain pipes.

2. A machine for treating canned goods 55 comprising a receptacle circular in cross section and having a can inlet and a can exit; a fixed helically directed rail secured to the receptacle wall and lying against the inner surface thereof, said rail forming one member 60 of a can track through which the cans are advanced through the receptacle; a rotatable annular series of spaced rails within the fixed helically directed rail, parallel with its axis and forming the other member of said can track; a header pipe outside of and longitudinally underlying the receptacle; a plurality of drain pipes leading from the header pipe and opening into the receptacle 65 between the coils of the helically directed rail therein; and a steam pipe housed within said header pipe.

In testimony whereof I have signed my name to this specification.

ALBERT R. THOMPSON.
